(57) **CLAIM**

The ornamental design for a bottle, as shown and described.

DESCRIPTION

FIG. 1 is a front elevational view of a bottle showing our new design, the rear elevational view being a mirror image; FIG. 2 is a left side elevational view thereof, the right side elevational view being a mirror image;

FIG. 3 is a top plan view thereof; and,
FIG. 4 is a bottom plan view thereof.

The phantom line showing of a dispenser in FIG. 1 is for illustrative purposes, and does not form part of the claimed design.
